UNITED STATES PATENT OFFICE

1,985,796

CAN OPENING AND SPOUT FORMING DEVICE

Joseph Howard Renshaw, Cincinnati, Ohio, assignor to Continental Can Company, Inc., New York, N. Y., a corporation of New York

Application April 23, 1934, Serial No. 722,047

2 Claims. (Cl. 221—23)

The invention relates to new and useful improvements in a device for opening a can and forming a spout in the side wall thereof.

An object of the invention is to provide a can opening and spout forming device wherein the inner shoulder of the double seam joining the can end to the can body at the point opposite where the spout is to be formed may be used as an abutment for supporting the operating tool during the forming of the spout.

A further object of the invention is to provide a can opening tool having an abutment device and a spout forming device which may be separated from each other for the forming of the spout by vertical pressure applied to the tool.

In the drawings—

Figure 1 is a side view showing the can piercing and spout forming device as applied to the can for piercing the end preparatory to the forming of the spout;

Figure 1a is a view showing on an enlarged scale and in bottom plan view the spout forming device;

Figure 1b is a side view of the same looking toward the spout forming shoulder;

Figure 1c is a bottom plan view showing the shape of one form of the abutment.

Figure 2 is a plan view of the same;

Figure 3 is a side view showing the tool as having been operated for the forming of the spout;

Figure 4 is a plan view of the can with the spout formed by the improved piercing and spout forming device, and

Figure 5 is a side view of the same with parts broken away in section.

It is a common expedient to package liquid products in hermetically sealed metal cans consisting of a body portion and ends double-seamed thereto. The product marketed in such cans is not only protected from contact with the air, but the contents of the can cannot be changed without giving physical evidence of the can having been tampered with. Lubricating oil is put up by the original dispensers in sealed cans and sold at the filling stations where they are opened in the presence of the customers and emptied into the chamber where it is to be utilized for lubricating purposes. This insures that the customer obtain the original product.

The present invention has to do with a tool for opening a container of the above type and forming a pouring spout in the side wall thereof. The tool includes an abutment lever 1 and a spout forming lever 2. The spout forming lever 2 consists of side members 3 and 4 which are spaced

from each other. These side members are integrally connected with a spacing block 5 at one end thereof, and are integrally connected to a cross bar 6 at the other end thereof.

Attached to this cross bar 6 is a combined piercer and spout forming device 7. This device consists of a vertical member through which screws 8, 8 pass for securing the same to the cross bar 6. There is also a horizontal member 9 which extends beneath the cross bar 6. This makes a very strong and durable connection of the device 7 to the cross bar 6, which will not be displaced when either a vertical pressure is applied to the cross bar or a lateral pressure applied thereto during the forming of the spout. Integral with the horizontal member 9 is a cutter having a piercing point 10. Said cutter is also provided with a curved shoulder 11. This curved shoulder inclines slightly to the longitudinal length of the cross bar so that when the parts are in the position shown in Fig. 1, the curved face 11 is substantially vertical. The cutting edge extends from a penetrating point at the center of the curved wall and inclines upwardly therefrom so that when the cutter is applied to the can end, it will pierce the can at the double seam and along lines leading therefrom.

In the drawings there is shown more or less diagrammatically a can of the type above described which consists of a body portion 12 to which an end 13 is secured by a double seam 14. When the tool is applied to the can, the cutter will penetrate the can at the point *a* and will tear the can along the line *a—b* in one direction and *a—c* in the other direction.

The abutment lever 1 is in the form of a skeleton bar which lies between the two side members 3 and 4 of the spout forming lever. A pivot bolt 15 extends through a hole in the cross bar and in the lever for joining the two levers. This pivot bolt is provided with a head at one side and a threaded nut at the other, so that it may be readily removed for disconnecting the levers, when desired. There are a series of holes in the side members 3 and 4 which are indicated at 16 in the drawings. There are a series of holes in the skeleton bar of the abutment lever which are indicated at 17. The purpose of providing a series of holes is to permit the tool to be adjusted for use on cans of different size.

The abutment lever 1 is provided with laterally projecting portions 18 at one end thereof, forming a flat handle member adapted to be pressed upon by the operator in the piercing of the can.

end and the forming of the spout. At the other end of the abutment lever is an abutment device 19. This abutment device has a vertical member and a horizontal member 20 which underlies the end of the bar forming the abutment lever. The vertical portion of this device extends up along the end wall of the abutment lever and is secured thereto by suitable rivets. This abutment device is provided with a curved depending lug 21. Said lug at the outer face thereof is curved to conform to the general curvature of the inner shoulder of the double seam of the can. This curved outer face of the abutment lug is inclined so that when the parts are in the position shown in Fig. 1, its outer face is substantially vertical. There is also a piercer 22 attached to this device 19 which projects below the abutment lug 21. In the operation of the tool, the abutment lug is preferably first placed against the shoulder of the double seam. The levers are then moved to a position where they are at an acute angle to each other, and the cutter 10 placed against the double seam or close to the double seam at a point diametrically opposite the point of engagement of the double seam by the abutment lug. The operator then applies pressure to the outer end of both levers, and this will cause the piercing point 22 to pierce the can end 13 forming an opening 23 therethrough. The downward pressure on the levers will cause the cutter 10 to cut the metal in the can end and it will also cause the levers to straighten out from their inclined position shown in Figure 1 to the position shown in Figure 3. As the cutter passes through the metal in the can end, it will be gradually moved away from the lug or abutment 21 and away from the double seam 14. As a result, the can end will be cut along the line *c—a—b* and the double seam and body wall adjacent the cut formed in the end will be forced laterally and outwardly and as the levers are forced to the straight line position they will cause the metal to rupture along the lines *d—d*, thus releasing the double seam and body wall from the end and permitting the same to be shaped into a spout as shown in Figure 4, wherein there is a pouring lip 14a and side walls leading to the pouring lip and merging in the body wall and double seam of the can body at their other ends. During this shaping of the spout, the can end will buckle upwardly as indicated at 13a and this will contract the double seam, moving it inwardly from the broken line position of Figure 4 to the full line position. In other words, the area of the top of the can end is decreased in order to give sufficient metal to form this pouring spout. The body wall directly beneath the double seam will be shaped in cross-section similar thereto and will gradually merge into the cylindrical body at a short distance below the double seam, as clearly indicated in the drawings. The forming tool is then removed and this leaves the can body with a well formed pouring spout and a vent hole at the opposite side thereof.

From the above, it will be apparent that a combined can end piercing tool and spout forming device has been provided which consists of two movable levers, one of which carries an abutment member adapted to contact with the double seam, while the other carries a spout forming device. Vertical pressure applied to these levers will first cause the can end to be pierced to form a vent opening and cut to release the can end from its connection to the double seam throughout a limited region and at a point diametrically oppo-

site the vent opening. Further pressure upon these levers from the toggle action thereof will cause the double seam and the can wall immediately connected thereto in the region of this cut opening to be bent outwardly into the form of a spout. The structure is very simple and is very efficient in its operation. The vertical pressure, in the first place, is used for moving the piercing and cutting members in a vertical direction, and the vertical pressure is then converted into a horizontal force applied to the double seam at diametrically opposite points for shaping the same into a spout.

In the specific form, as noted above, there is a piercer 22 at one end of the expanding device 15 and this is adjacent the relatively long lug 21. At the other end there is a cutter which cuts a large hole and the cutter is the sole means for contacting and expanding the can. It is understood, of course, that these parts may be differently constructed and of different dimensions. When the contact points of the can which are to cause expansion are similarly shaped, expansion will take place in both directions and at both sides of the can. That is, the expansion is 25 away from the center of the can at each side thereof. As in the present construction where the contact point with the double seam is relatively long and conforms to the inside circumference of the double seam, the expansion will 30 take place only at the end having the cutter 11 and when this expansion is great enough then the can end will part from the double seam at the point of expansion each side of the cutter. This aids in the releasing of the double seam and 35 the can body wall for the shaping of it into a spout. If it were desired to increase the air inlet or vent hole, the abutments and cutters could be proportioned so that there would be some expansion at both ends of the expanding tool.

It is understood that various changes in the details of construction and the shaping of the parts may be made without departing from the spirit of the invention as set forth in the appended claims.

Having thus described the invention, what I claim as new and desire to secure by Letters Patent, is:

1. A can opening and spout forming device comprising a member adapted to contact with the inner wall of the container end at the double seam, a second member adapted to contact with the wall of the container at the double seam and opposed to the first contact, said second-named member having means for rupturing the container end adjacent the wall of the can body, and means for forcibly actuating said members for forming a laterally projecting pouring spout in the double seam and body wall adjacent the point of rupture.

2. A can opening and spout forming device comprising an abutment lever having an abutment member adapted to contact with the inner shoulder of the double seam of a can, a spout forming lever pivoted to said abutment lever and having a spout forming device provided with a cutter for piercing the end of the container adjacent the double seam joining the end to the can body, and means for joining said levers whereby a vertical pressure applied to the outer ends of said levers will cause the cutter to pierce the can end and the spout forming device to shape the double seam and body wall so as to form a laterally projecting pouring spout.

JOSEPH HOWARD RENSHAW. 75
